UNITED STATES PATENT OFFICE.

MARY M. HERRICK, OF MARINETTE, WISCONSIN.

DESIGN FOR A CHILD'S TOY.

SPECIFICATION forming part of Design No. 20,484, dated January 20, 1891.

Application filed August 2, 1890. Serial No. 360,832. Term of patent 3½ years.

To all whom it may concern:

Be it known that I, MARY M. HERRICK, a citizen of the United States, residing at Marinette, in the county of Marinette and State of Wisconsin, have invented a new and original Design for Toys, of which the following is a specification.

My design for a child's toy consists, essentially, of a bell-shaped wire structure.

10 In the drawings, Figure 1 is a perspective view of my design. Fig. 2 is a plan view thereof.

15 In the drawings, the letter A designates a series of arched wires crossing at their centers, as shown at a, having their ends a' connected by means of a circular band of wire a², the whole having the general shape and appearance of a bell. From the point of in-

tersection of these wires a depends a link b, which supports a pyramidal bell B. 20

C designates pyramidal bells, which are suspended from the circular band from every other point of connection with the arched wires A.

I claim—

25 The design for a toy herein described and shown, the same consisting of a bell-shaped wire structure.

In testimony that I claim the foregoing as my own I have hereto affixed my signature in 30 presence of two witnesses.

MARY M. HERRICK.
